Primary Examiner—Melody N. Brown

Attorney, Agent, or Firm—Whyte Hirschboeck Dudek

[57] **CLAIM**

The ornamental design for a truck body—back end, as shown and described.

DESCRIPTION

FIG. 1 is a back perspective view of a truck body—back end showing our new design; and,

FIG. 2 is a side elevation, with the opposite side being a mirror image.

The broken lines shown in all figures are for illustrative purposes only and form no part of the claimed design.
